[57] **CLAIM**

The ornamental design for a pill-taking schedule monitor board, as shown and described.

DESCRIPTION

FIG. 1 is a top, front, and left side perspective view of a pill-taking monitor board showing my new design; FIG. 2 is a front elevational view thereof, the rear being plain and unornamented;

FIG. 3 is an exploded right side elevational view thereof, with the detachable pill container shown detached and partially opened; and

FIG. 4 is a bottom plan view thereof.

The broken-line depiction of pills and the broken-line depiction of lettering on the face of the board being for illustrative purposes only and forming no part of the claimed design.

FIG. 1

FIG. 2

FIG. 3

FIG. 4
